UNITED STATES PATENT OFFICE.

AID COLLINS LA MONDA, OF DAYTON, OHIO.

DESIGN FOR A GAME-BOARD.

SPECIFICATION forming part of Design No. 31,656, dated October 10, 1899.

Application filed September 5, 1899. Serial No. 729,560. Term of patent 7 years.

To all whom it may concern:

Be it known that I, AID COLLINS LA MONDA, a citizen of the United States, residing at Dayton, in the county of Montgomery and State of Ohio, have invented and produced a new and original Design for Game-Boards; and I do hereby declare the following to be a full, clear, and exact description of the invention, reference being had to the accompanying drawings, and to the letters of reference marked thereon, which form a part of this specification.

My invention relates to a design for a game-board, and is fully illustrated in the accompanying drawings, in which like characters of reference refer to similar parts throughout the several views, and in which—

Figure 1 is a perspective view of a game-board embodying my new and original design, and Fig. 2 is a somewhat enlarged vertical transverse sectional view of same.

As shown in the drawings, the essential or material features of my new and original design for a game-board consist of a base-board *a*, surrounded by a projecting vertical flange *b*, said base-board being formed or provided with raised inclined planes *c* and a series of pegs or small vertical projections *d*.

Having now described my invention, what I claim as new and original and as my invention, and desire to secure by Letters Patent, is—

The design for a game-board, as herein shown and described.

In testimony whereof I have affixed my signature in presence of two witnesses.

AID COLLINS LA MONDA.

Witnesses:

PAUL J. WORTMAN,
E. J. FINKE.
